(57) **CLAIM**

The ornamental design for a watch with display, as shown and described.

DESCRIPTION

FIG. 1 is a front perspective view of a watch with display according to the present invention;

FIG. 2 is a rear perspective view of the watch with display;

FIG. 3 is a top view of the watch with display;

FIG. 4 is a front view of the watch with display;

FIG. 5 is a bottom view of the watch with display;

FIG. 6 is a rear view of the watch with display.

FIG. 7 is a left side view of the watch with display; and,

FIG. 8 is a right side view of the watch with display.

The structural features depicted by broken lines have been shown for the purpose of illustrating portions of the watch with display that form no part of the claimed design.

1 Claim, 4 Drawing Sheets
